INVENTOR

UNITED STATES PATENT OFFICE.

EDWARD E. CLEMENT, OF WASHINGTON, DISTRICT OF COLUMBIA.

DESIGN FOR A POWDER PACKING AND DISPENSING BOX.

SPECIFICATION forming part of Design No. 33,284, dated October 2, 1900.

Application filed August 23, 1900. Serial No. 27,855. Term of patent 14 years.

To all whom it may concern:

Be it known that I, EDWARD E. CLEMENT, a citizen of the United States, residing at Washington, in the District of Columbia, have invented and produced a new and original Design for a Powder Packing and Dispensing Box, of which the following is a specification, reference being had to the accompanying drawings, forming part thereof.

Figure 1 is a side perspective view of a box, showing my new design. Fig. 2 is an end view of the same, looking from below.

As shown in the drawings, the leading or material feature of my design consists of a continuous groove or depression extending around the cylindrical surface of the box A, between its ends B and B'. These ends are

convex, being sections of the surface of a sphere of larger diameter than that of the box and join the cylindrical sides at an obtuse angle.

Having described my invention, what I claim, and desire to secure by Letters Patent, is—

The design for a powder packing and dispensing box, substantially as shown and described.

In testimony whereof I have signed my name to this specification in the presence of two subscribing witnesses.

EDWARD E. CLEMENT.

Witnesses:

CHAS. J. O'NEILL,
JOHN P. CAMPBELL.
